POWER SAW MITRE BOX

Stuart R. Ferguson, 2155 Coldwater Canyon Drive,
Beverly Hills, Calif.

Filed Jan. 3, 1961, Ser. No. 63,426

Term of patent 7 years

(Cl. D93—4)

I claim:
The ornamental design for a power saw mitre box, as shown.
